UNITED STATES PATENT OFFICE.

ARABELLA R. HORLICK, OF RACINE, WISCONSIN.

DESIGN FOR A DOUGH-RAISING CABINET.

46,365.

Specification for Design.

Patented Sept. 8, 1914.

Application filed June 6, 1914. Serial No. 843,586. Term of patent 7 years.

To all whom it may concern:

Be it known that I, ARABELLA R. HORLICK, a citizen of the United States, residing at Racine, in the county of Racine and State of Wisconsin, have invented a new, original, and ornamental Design for Dough-Raising Cabinets, of which the following is a specification, reference being had to the accompanying drawing, forming part thereof.

The drawing represents a perspective view of the dough raising cabinet.

I claim:

The ornamental design for a dough raising cabinet as shown.

In testimony that I claim the foregoing I have hereunto set my hand at Racine, in the county of Racine and State of Wisconsin, in the presence of two witnesses.

ARABELLA R. HORLICK.

Witnesses:

G. D. PEAZ,
Wm. HORLICK, Jr.
